W. K. Miller

ATTORNEY

UNITED STATES PATENT OFFICE.

JOHN CLASS, OF CANTON, OHIO.

SEESAW AND MERRY-GO-ROUND.

SPECIFICATION forming part of Letters Patent No. 368,652, dated August 23, 1887.

Application filed May 20, 1887. Serial No. 238,881. (No model.)

To all whom it may concern:

Be it known that I, JOHN CLASS, a citizen of the United States, and a resident of Canton, county of Stark, State of Ohio, have invented a new and useful Improvement in Seesaws and Merry-Go-Rounds, of which the following is a full, clear, and exact description, reference being had to the accompanying drawings, making part of this specification.

10 My invention relates to improvements in seesaws and merry-go-rounds; and it consists in providing a combined seesaw and merry-go-round, as hereinafter described.

15 My invention relates to the detail and combination of parts, as described, and set forth in the claims.

20 Figure 1 is an elevation of a seesaw and merry-go-round, representing my improvements. Fig. 2 is a like view, partly in section. Fig. 25 3 is a view in perspective of my invention adapted to a portable stand or base. Fig. 4 is a sectional view of the same.

Similar letters of reference indicate corresponding parts in all of the figures of the accompanying drawings.

25 Letter A represents a post or stand that may be planted on the lawn or elsewhere, on the top of which there is mounted a cast-metal socket, B, the upper end of which terminates in a 30 spherical head or ball-shape portion, a. About the lower end of said socket there is provided an annular groove, a'. On the apex of the head a there is a segmental slide, a'', the circle of the under side of the slide to coincide with the surface of the head a, with which a pivotal connection is formed by the rivet a'', about which the slide a'' may rotate.

35 A saddle-piece, C, is provided, having about central thereto a hemispherical socket, a'', in 40 which there is provided a semi-annular groove, a'', in the line of the saddle-wings a'', the size of said groove to be regulated by the size of the slide a'', over which it will move as the saddle is vibrated over the head. The object of the 45 slide and groove is to prevent a side rocking movement of the saddle and yet allow it to vibrate freely over the head in the line of its length. On the outer ends of the saddle-wings a'' there are provided downwardly and outwardly projected lugs a'', having pivoted between them a latch, a'', and on the top a stud, a'', and from the center of the saddle an up-

wardly-projected bolt, b'', by which the said plank D is secured to the saddle C. From the center of the saddle, as at b, there is a through-slot, b', in the plank C, adapted to the bolt b'', 55 extending longitudinal to b'', and a groove, b'', on the under side extending to b'', in which rests the lug a''.

In the groove a' there is a ring, b'', having 60 trunnions b'' and eyes b''. The said ring a' is divided in two parts, said division being central through the trunnions, the two parts being duplicates. Link E has a pivotal connection about the trunnion b''. The side link 65 is provided with an adjustable loop, b'', the free end of which is adapted to pass over the end of the saddle-wing a'' and rest on the end of the latch a'', and to the eyes b'' is attached coil-springs F, the outer end of which is provided 70 with a loop, d, adapted to pass over the end of the saddle-wing a'' and rest on the latch a''.

The seat-plank D has on each end a back-rest, G, formed of a single piece of wire, and in form substantially as shown, beginning at 75 the front middle section, as at d', and extended outwardly and upwardly to a point designated as d'', and inwardly to d'' and downwardly to d'', thence to the point designated as d'', at which point the free ends d'' are secured to the central 80 portion, d', of the wire, and at which point the parts are clasped together by metal clasp d'' about the parts, and by which the rest may be secured to the plank by a bolt, d'', about which said rest may be adjusted for a side seat or 85 astride. The seat-plank D may be in two parts, connected by the hinge d''' and secured by the splice-block d''.

It will be seen that the seesaw may be vibrated in any direction over the head a, the 90 slide a'' moving about the pivot a'', but can have no rocking side motion. To apply the springs, pass the loops d over the latch a''. With both springs applied the saddle cannot be thrown from the head, making the use of either the 95 seesaw or merry-go-round safer for children; or one spring may be dropped down and the seesaw used by one child.

Whether the springs are connected with the saddle or not, my invention may be used as a 100 seesaw or merry-go-round, or both at the same time, as the rotary and vibratory movements may be simultaneous; and to adapt the parts to be used as a merry-go-round for one person,

the link E may be connected with the saddle, as shown in Fig. 1, the person seated on the opposite end of the plank. Whether this cheek-loop or the springs are in use, the ring b^5 will 5 revolve about the socket B in the groove a^3 and the groove a^6 , vibrating over the slide a^2 as the ends of the seat-plank rise and fall.

The seat-plank may be adjusted endwise over the saddle to adapt the seesaw to persons of unequal weight, and secured in such adjustment by the thumb-screw b^9 .

For the purpose of adapting my invention to nursery and other indoor use, I have provided a tripod for the support of the hereinabove-described seesaw and merry-go-round, consisting of a central vertical stem, H, preferably of metal pipe, surmounted by the spherical or ball-shaped portion a^1 and slide a^2 , a leg-support, h' , embracing said stem H, having 20 flanged projections h^4 , for the reception and support of the legs h^4 , the said legs having a link-connection, h^5 , with the bottom of the stem H, as shown. The stem H is also provided with a series of perforations, h^6 , and a pin, h^7 , 25 by which the height of the seesaw and merry-go-round may be adjusted.

Having thus fully described the nature and object of my invention, what I claim, and desire to secure by Letters Patent, is—

30 1. In a seesaw and merry-go-round, the combination of the head a^1 , the upper portion of which is spherical, and the upwardly-projected slide a^2 , pivoted thereto, and a saddle, C, having a hemispherical socket, a^4 , and groove a^5 , substantially as shown and described, and for the purpose set forth.

2. In a seesaw and merry-go-round, the combination of the head a^1 , the upper portion of which is spherical in form, an upwardly-projected pivot, a^3 , and a saddle, C, having a hemispherical socket, a^4 , and groove a^5 , said

saddle adapted to be vibrated over and rotated about said pivot, substantially as and for the purpose set forth.

3. In a seesaw and merry-go-round, the combination, with the stand A, of the socket B, having an annular groove, a^3 , spherical head a^1 , and a saddle, C, having a hemispherical socket, a^4 , and projected wings a^6 , having on their outer ends latches a^8 , ring b^5 , and springs 45 F, substantially as described, and for the purpose set forth.

4. In a seesaw and merry-go-round, the combination, with the standard A, of the socket B, having an annular groove, a^3 , spherical head a^1 , 55 an upwardly-projected slide, a^2 , a saddle, C, having a hemispherical socket, a^4 , groove a^5 , wings a^6 , latches a^8 , ring b^5 , loop E, and seat-plank D, substantially as described, and for the purpose set forth.

5. In a seesaw and merry-go-round, the combination, with the seat-plank, of the saddle C, having a hemispherical socket, a^4 , groove a^5 , a spherical head, a^1 , slide a^2 , standard H, having perforations h^6 , pin h^7 , and a tripod having 65 legs h^4 , the upper ends of which are pivotally connected to the support-ring h' , the lower end by a link to the standard H, substantially as shown and described, and for the purpose set forth.

6. In a seesaw and merry-go-round, the combination, with the seat-plank, of the seat consisting, essentially, of a wire or rod bent into shape to form the sides and back of a seat and secured to the plank in rotary adjustment, substantially as set forth.

In testimony whereof I have hereunto set my hand this 14th day of May, A. D. 1887.

JOHN CLASS.
